SAFETY SHOE

Earle F. Baird, Waltham, Mass., assignor to The
B. F. Goodrich Company, New York, N. Y., a
corporation of New York

Application August 1, 1941, Serial No. 405,046

2 Claims. (Cl. 36—77)

This invention relates to footwear, and more especially to safety shoes for protecting the feet against injury.

Heretofore it has been proposed to provide boots and shoes with a stiff toe cap of metal built into the article over the toes of the wearer to prevent crushing of the toes by heavy objects falling on the toe of the article.

Due to the rigid nature of the metal toe reinforcement, it has been found difficult to construct such shoes properly, as the metal parts, even when cast from the same pattern or formed in the same die have varied considerably in dimensions and the lasts upon which the shoes have been built have also varied in dimensions. It has been found that no matter how carefully the toe portion of the shoe has been designed and constructed, normal manufacturing variations have caused such looseness of fit or air space between the last and the metal toe reinforcement as to prevent entirely satisfactory adhesion of the lining to the metal toe reinforcement. This loose lining condition has been undesirable as the wearer's toe has quickly worn through the lining and has been exposed to contact with the metal. The worn lining has bunched and wrinkled, causing injury of the toes of the wearer.

The present invention aims to overcome these difficulties and others, and to provide an improved product. The principal objects of the invention are to provide improved protection for the toes of the wearer, to provide effective cushioning of the toes from the metal toe reinforcement, to provide for compensating for variation between the metal parts and the lasts, to provide improved adhesion of the parts of the shoe, and generally to provide facility of manufacture and neatness of construction.

These and other objects will appear from the following description and the accompanying drawing.

Of the drawing:

Fig. 1 is a perspective view of the toe of an article of footwear embodying the invention, 45 other parts being broken away.

Fig. 2 is a cross-sectional view thereof taken on line 2—2 of Fig. 1.

Fig. 3 is a perspective view of the lasted article as partially completed, parts being broken away.

Fig. 4 is a plan view of the cushioning material prior to assembly in the shoe.

Fig. 5 is a sectional view thereof, taken on line 5—5 of Fig. 4.

In accordance with the invention, a layer of 55

unvulcanized sponge rubber or other rubber-like composition is assembled with other parts of the shoe and is positioned between the lining of the shoe and the metal toe cap so that during vulcanization of the article, the composition is blown to provide a sponge rubber cushion completely filling the space between the metal toe cap and the lasted lining regardless of the dimensions of the space therebetween, and in the finished shoe provide for cushioning the toes of the wearer from the rigid metal toe cap.

Referring to the drawing, the shoe comprises an insole 10 which in the construction of the shoe is laid over the sole of a last, and a rubberized fabric lining 11 which is drawn over the last and cemented over the insole at its margins 12. A cushion 13 of sponge rubber is secured on one face to the lining 11, and on the other face to a rubberized fabric toe cap 14. A metal toe cap 15 is adhered to the fabric 14. A gum strip 16 extends over the toe between the fabric toe cap and the lining at the margin of the sponge rubber cushion and directly under the margin of the metal toe cap. The upper 17 of the shoe is lasted over the metal toe cap. A filler sole 18 is applied over the insole within the space provided by overlapping margins 19 of the upper, and an outsole 20 is secured over the filler sole and the margins 19 of the upper. All of the parts are secured to each other by vulcanization.

In building the shoe, unvulcanized sponge rubber composition and the gum strip 16 are assembled on the rubberized fabric toe cap 14 and are cut to shape, as shown in Figs. 4 and 5. The insole and lining are assembled over a last and the assembled fabric toe cap and sponge composition are cemented in place over the lining. The assembled materials may be notched as at 21 to provide for forming them about the sharp curvature of the toe. The metal toe cap 15 is then cemented over the fabric toe cap. The upper is applied over the metal toe cap and its margins are turned over the insole. The filler sole and the outsole are then applied in succession and cemented in place. The assembled article is then subjected to heat to vulcanize the rubber material.

During vulcanization, the sponge rubber composition which contains a blowing agent is blown or sponged by the heat so that it expands to completely fill the space between the lining and the metal toe cap regardless of the dimensions of the last and the metal toe cap. The sponge rubber material becomes vulcanized with the other rub-

ber materials, providing a cushion over the toes of the wearer to protect them from the metal.

The gum strip 16 provides a more solid cushion under the rear edge of the metal toe cap to prevent cutting of the foot should the metal be crushed.

Variations may be made without departing from the scope of the invention as it is defined by the following claims.

I claim:

1. An article of footwear comprising an outsole, a metal toe cap mounted on said outsole, an upper extending about the toe cap with its margins secured to the sole, a fabric lining secured to the upper rearwardly of the toe cap and extending under the toe cap to the sole of the article in spaced relation to the inner surface of the toe cap substantially throughout the extent of said surface, and a cushion layer of sponge rubber material substantially filling the space between the lining and the toe cap and extending from the rear margin of the toe cap to the sole of the article, said cushion layer being bonded to the toe cap and the lining throughout

their cushion contacting surfaces and providing an enclosing cushion for the toes of the wearer.

2. An article of footwear comprising an outsole, a metal toe cap mounted on said outsole, an upper extending about the toe cap with its margins secured to the sole, a fabric lining secured to the upper rearwardly of the toe cap and extending under the toe cap to the sole of the article in spaced relation to the inner surface of the toe cap substantially throughout the extent of said surface, a protective strip of dense soft rubber material secured along the rear margin of the toe cap between the inner surface of the toe cap and the lining, and a cushion layer of sponge rubber material substantially filling the space between the lining and the toe cap and extending from said strip to the sole of the article, said cushion layer being bonded to the toe cap and the lining throughout their cushion-contacting surfaces and providing an enclosing cushion for the toes of the wearer.
